INVENTOR.
FRANK J. MILLER.

BY *Jesse P. Stone*
ATTORNEY.

UNITED STATES PATENT OFFICE

FRANK J. MILLER, OF HOLLYWOOD, CALIFORNIA

PUMP

Application filed September 20, 1929. Serial No. 393,898.

The invention relates to a pumping device for raising liquids from wells and particularly to devices where the liquid is raised by fluid pressure.

5 It is one of the objects of the invention to devise a mechanism which may be readily inserted into the well bore whereby pressure may be exerted upon the liquid being raised.

Another object of the invention is to devise 10 a novel seat for the tubing.

A still further object of the invention is to arrange an automatically operable valve within the pump tubing.

It is also an object of the invention to devise 15 a mechanism which will operate automatically depending upon the rock pressure in the well.

Another object of the invention is to arrange 20 the pumping mechanism in such a manner that the single movable element may be readily removed.

Another object of the invention is to devise 25 a seat in the well bore which will permit a fluid pressure to be exerted at a point below the automatic valve mechanism.

Other and further objects of the invention will be readily apparent to those schooled in the art to which the invention appertains when the following description is considered 30

in connection with the accompanying drawing:

Fig. 1 is a more or less diagrammatic view 35 of my improved mechanism installed in a well, certain parts being broken away and shown in section for purposes of clearness.

Fig. 2 is an enlarged sectional view with certain parts broken away to show the detailed construction of the valve and seating structure.

40 By having reference to Fig. 1 a well bore is indicated at 2 and is here shown as having the usual casing 3 therein. This casing has a casing head such as 4 mounted at the top thereof. This casing head may be of any desired construction but I have shown it as provided with inlet or outlet pipes 5 and 6 which are each shown as being equipped with a shutoff valve 7. Mounted on the casing head 4 is shown a bushing 9 fitted with a tapered collar or holding member 10. This

member is adapted to engage the string 11 of pipe which is adapted to extend to a point adjacent the bottom of the well bore. In carrying out my invention I also mount a string of tubing 12 within the pipe string 11. The tubing may be supported by means of a head 13 and bushing 14 or in any other manner desired. I have shown an inlet 16 provided with a valve 17 to the space between the pipe 11 and the tubing 12. It is to be understood that the tubing 12 leads off to a storage tank or pipe line as desired in any manner to receive the liquid from the well.

By having reference to the lower portion of Fig. 1, I have shown the pipe string 11 as broken away to illustrate the arrangement of the valve seat. Fig. 2, however, shows an enlarged sectional view of this structure. The pipe 11 is provided on its inner surface with an annular ring 20 which is preferably fixed rigidly to the pipe section 11. This ring has a plurality of openings 21 therein to which the pressure tubes 22 are connected. These tubes extend downwardly and inwardly to a T coupling 23. The coupling 23 has a nozzle 25 fixed to the T outlet therefrom. This nozzle 25 may be of any desired length or size to accommodate the conditions existing in any particular well.

I have shown a plug 27 as being fixed on the nozzle 25. The structure which has just been described is all mounted within the pipe section 11 and lowered into the well. It is to be understood that the distance between the ring 20 and a nozzle 25 may be varied to obtain the most efficient production of liquid. It will be noted that this structure contains no moving parts but may be inserted into the well and remain there permanently.

Fig. 2 also shows the construction of the automatic valve and pressure nozzle which form the novel construction of my pump. The tubing is shown at 12 and has fixed on its outer surface a tapered collar 30. This collar is adapted to fit upon the tapered seat 31 of the ring 20. In this manner the weight of the tubing will be supported upon the ring 20. It will be noted, however, that the tubing 12 extends below the collar 30 and is threaded at 32 in a manner to be attached to the plug 27.

which has an opening 52 therein to fit over the nozzle 25. The tubing 12 is lowered into the well inside of the string of pipe 11 until the lower end comes in contact with the nozzle 25. It may then be moved downwardly until the tapered ring 30 engages in its seat 31. This will form a tight connection at the lower end of the tubing and will form a chamber 33 in the pipe 11 below the ring 20. A plurality of openings 35 have been shown in the tubing 12 to permit the entrance of the liquid from the strata and from the area within the casing 3. With this arrangement it will be seen that no liquid from the well is intended to enter the space between the string 11 and 12 and above the ring 20.

Within the tubing 12 I have shown a flange 40 to which is fixed a discharge nozzle 41. This insert is shown as tapered and conical in form and arranged to discharge upwardly. Above the upper end of this nozzle 41 I have shown a ring valve 43 which is adapted to sit upon a shoulder 44 and is normally retained in a seated position upon the upper end of the nozzle 41 by means of a spring 45. A band 46 is shown as arranged within the tubing to form an abutment for the upper end of the spring 45. A small flange 47 is shown on the valve to retain the spring 45 in proper position. A plurality of openings 50 are shown in the string of tubing 12 at a point below the valve 43 and above the ring 20.

The operation of my improved pump is as follows:

25 A fluid pressure may be forced through the inlet pipe 16 into the area between the tubing and the string of pipe. This pressure will pass through the openings 21 and the pipe 22 and be discharged through the nozzle 25. 40 This discharge of fluid will pass upwardly through the nozzle 41 and any accumulation of liquid in the tubing 12 will be raised upwardly to the surface. Any additional liquid flowing into the well may enter the opening 45 and be forced upwardly by the fluid pressure. By this arrangement it will be seen that a fluid pressure upon the inlet 16 will serve to raise a considerable quantity of liquid. However, when the rock pressure decreases or the amount of liquid in the well is 50 small it may be desired to provide an additional means of raising the liquid and to accomplish this I have provided the automatic valve arrangement 43.

55 It will be noted that this valve sits on top of the tapered discharged nozzle 41 and is normally held in seated position by the spring 45. However, when the fluid pressure through the inlet 16 is increased the pressure will increase between the pipe and the tubing and will pass through the opening 50. When this pressure exceeds the pressure in the tubing and resistance of the spring 45 the valve 43 will be raised from its seat on the discharge nozzle 41. As the valve rises away from its

seat an additional flow of fluid will occur past the nozzle 41 and assist in raising the fluid from the well.

It is believed that the arrangement of the present structure is of particular advantage in wells which are heading and which flow intermittently under a constant fluid pressure as the additional flow of fluid through the openings 50 will serve to lift the additional head of liquid which occurs periodically in the well. 70 75

The inlets and outlets 6 and 7 are provided so that if desired a pressure may also be exerted between the casing 3 and the string of pipe 11 or they may be used to force an additional supply of fluid into the well bore if desired. 80

Having thus described the invention what I desire to secure by Letters Patent is:—

1. In a pump, a pipe, a tubing therein, a ring on said pipe adjacent the lower end, means to make a seal between said ring and said tubing, a nozzle at the lower end of said tubing and means connecting the space above said ring with said nozzle whereby fluid may be projected up through said nozzle, a Venturi passage above said nozzle, and means to flow fluid upwardly outside said Venturi passage within the said tubing. 90

2. In a pump, a pipe, a tubing therein, means to allow pressure fluid to be forced downwardly between said tubing and pipe, a ring on the inner side of said pipe adjacent the lower end of said tubing, a tapered seat in said ring, means on said tubing to fit said seat, tubes to conduct fluid from above said ring to the lower end of said tubing, said tubing having inlet openings in addition to said tubes above said ring and an upwardly opening valve resisting the entrance through said openings with a predetermined pressure. 95 100

3. In a pump, a pipe, a tubing spaced inside said pipe, a nozzle extending into the lower end of said tubing axially thereof, a fluid conducting line from said pipe to said nozzle, an upwardly tapered passage above said nozzle, an inlet to said tubing at the lower end of said passage and outside said passage, and a ring valve controlling the passage of fluid to said tubing from said inlet at the upper end of said passage. 110 115

4. In a pump, a pipe, a tubing spaced inside said pipe, a nozzle extending into the lower end of said tubing axially thereof, a fluid conducting line from said pipe to said nozzle, an upwardly tapered passage above said nozzle, an inlet to said tubing at the lower end of said passage and outside said passage, and a ring valve controlling the passage of fluid to said tubing from said inlet at the upper end of said passage, said passage being flared outwardly through said valve to form a Venturi chamber. 120 125

5. In a pump, a pipe, a tubing spaced inside said pipe, a nozzle extending into the 130

lower end of said tubing axially thereof, a fluid conducting line from said pipe to said nozzle, an upwardly tapered passage above said nozzle, a ring valve closing the space about the upper end of said passage and said tubing, and means to hold said valve resiliently seated, there being an inlet through the wall of said tubing to said space.

In testimony whereof I hereunto affix my signature this 5th day of September, A. D. 1929.

FRANK J. MILLER.
